UNITED STATES PATENT OFFICE.

LEWIS P. SPENCER AND WILLIAM H. WILSON, OF NEW BEDFORD, MASSACHUSETTS.

SHUTTLE.

Application filed May 19, 1926. Serial No. 110,153.

This invention relates to certain new and useful improvements in shuttles and pertains more particularly to shuttles of the hand threaded type.

5 The primary object of the invention is to provide a shuttle which has new and improved means for enabling same to be easily and quickly threaded, and which at the same time prevents accidental movement of the 10 thread out of its operative relation to the shuttle.

The invention still further aims to provide means of the type mentioned which can be economically produced and easily and 15 quickly applied to the shuttle and which is also positive and certain in operation.

In the drawings:—

Figure 1 is a top plan view of the invention applied to a shuttle, the latter being 20 shown in fragment.

Figure 2 is a side elevation;

Figure 3 is a view similar to Fig. 1, but showing the upper member of the device removed;

25 Figure 4 is a section on line 4—4 of Fig. 1.

Figure 5 is a section on line 5—5 of Figure 1,

Figure 6 is a detail side elevation of the upper member of the device;

30 Figure 7 is a similar view of the other side of the upper member;

Figure 8 is a side elevation of the lower member of the device and

Figure 9 is a section on line 9—9 of Fig. 8.

35 In proceeding in accordance with the present invention, a shuttle 1 is employed having the usual delivery eye 2, into which slot 3 extends, the latter further extending through the top of the shuttle.

40 The present invention provides a two-part device wherein the top or upper part or member 4 assists in retaining the lower part or member 5 in position.

The top member 4 has a front lip 6 of

45 V-form in plan view and which curves downwardly as shown in Fig. 6 and has a curved depending flange 7 along its front side, which flange has a part 8 disposed along the inner side of the top member. A hook 9 extends

50 downwardly from the top of the top member at the front thereof and a longer or larger hook 10 also depends from the top of the top member but is located at the rear thereof. A shank 11 depends from the top

55 of member 4 and has an extension 12, which

cooperates with the flanges 7 and 8 to form a socket 13 for a purpose to be later described.

Shank 11 has a base 14 provided with a concave upper face 15 that cooperates with the rear hook 10 to form a thread guide or passage 16. A stud 17 depends from base 14 and is received in a hole 18 provided therefor at the bottom of the usual shuttle cavity. The base 14 further has a lateral projection 19 which is received in a channel 20, the latter leading into a depression 21 which is formed to receive the base 14. The top of the member 4 further has a ledge 22 projecting outwardly from its outer side and which fits in a cut-out 23 formed therefor in the shuttle.

It will be thus noted that the top part is effectively held in position.

The bottom part or member 5 is preferably made of porcelain and has a side rib 25 and a depending leg 26 which parts are received in cut-outs provided therefor in the bottom of the shuttle cavity. A thread receiving eye 27 extends transversely through the member 5 and is guarded by a pair of fingers 28.

The upper end 29 of member 5 is shaped to be conformally received in the socket 13 at the under side of the top member 4, whereby the latter serves to hold the lower member in position, and permits ready removal of the lower member upon removal of the upper member. A screw 31 passes through hole 31 in base 14 and thus holds 90 both parts 4 and 5 in place.

To further rigidly hold part 5 in place due to its being made of porcelain, a substantially J-shaped bolt 33 is employed, the upper end 34 of which is received in an opening provided therefor in the upper end of part 5. The lower end of bolt 33, extends through the shuttle bottom and has a nut 35 thereon, by means of which the part 5 can be drawn downwardly to engage firmly in its seat.

In operation, to thread the device, the thread is engaged with the lip 6 and with the upper parts of hooks 9 and 10 (Fig. 1) and then moved downwardly, and under hooks 9 and 10 and under the hooks 28, entering eye 27 and the delivery eye 2 of the shuttle. Thus the thread is guarded by four hooks 9, 10 and 28, 28 so as to prevent accidental unthreading of the shuttle.

Having thus described our invention what we claim as new and desire to secure by Letters Patent is:—

1. In combination with a shuttle, a lower member having a leg and a side rib received in cut-outs provided therefor in the shuttle and having a top and a transverse eye, a pair of fingers guarding the eye, and a top member having a lip on its outer side, a shank having a base formed with a concaved part, a hook extending over the concaved part, a side projection and a depending stud on the base, the base projection and stud being received in cut-outs provided therefor in the shuttle cavity, the under face of the top of the top member being formed with a socket receiving the top of the lower member, a hook on the lip at the inner side of the top member and a pin extending through the shank of the base to hold the two members in position.
2. In combination with a shuttle, a lower member having its lower part seated in a cut-out provided therefor in the shuttle cavity, an upper member having a socket receiving the upper part of the lower member therein, means to secure the upper member in position, a pair of hooks on the upper member, the lower member having an eye communicating with the delivery eye of the shuttle, and a pair of hooks guarding the eye of the lower member.
3. In combination with a shuttle, a lower member having its lower part seated in a cut-out provided therefor in the shuttle cavity, an upper member having a socket receiving the upper part of the lower member therein, means to secure the upper member in position, and guarding means for the thread on the upper member, the lower member having an eye communicating with the delivery eye of the shuttle.
4. In combination with a shuttle, a lower member having its lower part seated in a cut-out provided therefor in the shuttle cavity, an upper member having a socket receiving the upper part of the lower member therein, means to secure the upper member in position, an upper and a lower hook on the upper member and a pair of hooks on the lower member.
5. In combination with a shuttle, a lower porcelain member having thread engaging means, means engaging the upper portion of the member to fixedly secure same to the shuttle, an upper member disposed completely over the top of the lower member and over the part of the securing means which engages the porcelain member having thread engaging means, and means to fixedly secure the upper member to the shuttle independently of the lower member so as to prevent breakage of the latter.
6. In combination with a shuttle, a lower porcelain member having thread engaging

means, means to fixedly secure the lower member to the shuttle, an upper member disposed over the lower member and having thread engaging means, and means to fixedly secure the upper member to the shuttle independently of the lower member so as to prevent breakage of the latter, said upper member having a socket closed at its top and receiving the lower member therein so as to conceal and protect the latter.

7. In combination with a shuttle, a lower member seated in a cut-out provided therefor in the shuttle, a substantially J-shaped securing element engaged at one end in a hole provided therefor in the upper part of the lower member and having the opposite end extending through an opening provided therefor in the shuttle, a nut on the last named end of the bolt to hold the element and thereby the member in position, an upper member engaged over the lower member, means to secure the upper member in position, and thread guiding means to secure the upper member in position, and thread guiding means on the respective members.

8. In combination with a shuttle, a lower porcelain member having thread engaging means, means to fixedly secure the lower member to the shuttle, an upper member disposed over the lower member and having thread engaging means, and means to fixedly secure the upper member to the shuttle independently of the lower member so as to prevent breakage of the latter, said upper member completely overlying the lower member so as to conceal and protect the latter.

9. In combination with a shuttle having a cut-out, a porcelain member conformably seated in the cut-out, means engaged with the top of the member to fixedly secure same in the cut-out, an upper member having a top formed with a socket conformably receiving the upper end of the lower member and engaged over the part of the securing means that engages the top of the porcelain member and having a depending shank, said shuttle having a depression to one side of the cut-out, which depression provides a seat for the base of the shank, means to secure the upper member in position, and cooperating thread engaging means carried by the members.

10. In combination with a shuttle having a cut-out, a porcelain member seated in the cut-out, means engaging the top of the member and the bottom of the shuttle to clamp the member in the cut-out, an upper member overlying the lower member and the clamping means thereof, and means to secure the upper member in position, said members having cooperating thread engaging means.
